(57) **CLAIM**

The ornamental design for a seven scallop bowl with wicker appearance, as shown and described.

DESCRIPTION

FIG. 1 is a front perspective view of an embodiment of a seven scallop bowl showing our claimed design.

FIG. 2 is a top plan view of the bowl of FIG. 1.

FIG. 3 is a front elevational view of the bowl of FIG. 2.

FIG. 4 is a rear elevational view of the bowl of FIG. 2.

FIG. 5 is a right side elevational view of the bowl of FIG. 2.

FIG. 6 is a left side elevational view of the bowl of FIG. 2.

FIG. 7 is a bottom plan view of the bowl of FIG. 2; and,

FIG. 8 is a cross-sectional view of the bowl of FIG. 2 taken in the direction of cutting plane 8-8 of FIG. 2.

The broken lines represent portions of the structure that form no part of the claim.

Our new seven scallop bowl design is characterized by a woven wicker appearance.
